SAND AND GAS TRAPS FOR OIL WELLS
George Franklin Le Bus, Wichita Falls, Tex.
Application May 23, 1950, Serial No. 163,766
5 Claims. (Cl. 210—51)

This invention relates to improvements in sand and gas traps for oil wells and more particularly to sand and gas traps that are placed below the working barrel of the oil well pump to remove the sand from the crude oil, or the greater portion therefrom before the oil enters the pump, to present a barrier or trap against the entrance of gas into the tubing so as to maintain the gas in the subterranean reservoir so as to lengthen the life of the oil well by maintaining pressure on the strata to insure the flowing of oil in the strata to the well from which the oil is being pumped.

In the pumping of deep wells, the use of metal to metal pumps, that is pumps with metal plungers operating within metal cylinders is very desirable, and, in fact necessary after the hydrostatic column of fluid being pumped exceeds the yield point of rubber, fibre, or fabric cups or rings. When metal to metal pumps are subjected to gas and sand that normally occurs in the fluid being pumped from the well, the coacting parts wear rapidly, which reduces the efficiency of the pump, causes loss of production and increases the cost of pumping as well as requiring frequent replacement of pump parts and pumps.

The present invention provides a combination sand and gas trap whereby the liquid being pumped enters the top of the trap and no gas will enter the trap so long as the inlet opening is submerged in the liquid, as the gas is lighter than the liquid and rises to the top of the oil, either to flow out through the casing or to be maintained in the well to maintain pressure on the producing strata.

An object of this invention is to provide a sand and gas trap wherein the sand, or a major portion thereof, is removed from the crude oil or fluid that is being pumped before the entry of the oil into the pump, and to restrain gas from entering the pump as long as the inlet of the pump is submerged in the oil.

Another object of the invention is to provide a sand and gas trap with removable sections so the trap may be varied in length to accommodate the trap to varying conditions and to different wells.

Another object of the invention is to provide a sand and gas trap that is readily assembled and disassembled for the removal of the sand therefrom, or for the replacement of parts.

A still further object of the invention is to provide a sand and gas trap in which the sand trap reservoir may be varied in length to receive and hold the sand extracted from the oil over a long operating period, thereby reducing the operating overhead by making unnecessary frequent pulling of the tubing for the removal of the sand from the trap.

A still further object of this invention is to provide a sand and gas trap having the opening at the top thereof to receive the oil in the trap, and which trap will prevent the entry of gas into the trap as long as the inlet pipe is submerged in the oil so as to prevent a

2

gas lock in the pump and prevent the beating out of the valves and seats in the pump.

Another object of this invention is to provide a sand trap that has a series of baffles and tubes so that the sand entrained in the crude oil settles out by stages before it reaches the pump.

An embodiment of this invention is illustrated in the accompanying drawings, in which:

Fig. 1 is a sectional view through the lower portion of a deep well showing the tubing having a gas and sand trap mounted at the lower end thereof in elevation;

Fig. 2 is an enlarged vertical sectional view through the sand trap, with parts broken away and shortened to bring out the details of construction;

Fig. 3 is a perspective view of a baffle unit removed from the trap;

Fig. 4 is a fragmentary perspective view partly in section and with parts shown in elevation to show how 20 the baffle members are interposed between the sections of pipe;

Fig. 5 is a vertical sectional view of the upper portion of one of the upstanding tubes showing a diverting cap thereon in full line and also showing an adjusted position of the diverting cap in dashed outline; and

Fig. 6 is an enlarged vertical sectional view through a joint of the inlet pipe showing the manner in which the joint is connected and sealed.

With more detailed reference to the drawing the number 1 designates the lower portion of a deep well having casing 2 therein, with tubing 3 positioned within the casing 2. The lower end of the tubing 3 has a pump 4 positioned thereon to which a gas and sand trap, generally designated at 5, is attached at the lower end. The gas and sand trap is preferably of greater diameter than the tubing 3. The gas and sand trap 5 comprises an upper tubular shell member 6, one or more intermediate tubular shell members 7, and a lower trap or reservoir comprising a tubular shell member 8, which members are screw threaded together in such manner as to receive and hold baffle members 9 therebetween. The baffle members 9 each have a large central inlet tube 10 positioned therein so as to complementarily fit in end to end relation with the other tubular members 10 and with the uppermost end of the central inlet tube 10 interfitting with the lower end of a lateral tube 11 leading to the exterior of upper shell member 6. The inlet pipe 10 directs the fluid downward into reservoir 12, which reservoir is of increased cross sectional area, which causes the flow of oil therethrough to become slower and permits the greater portion of the sand to settle downward into reservoir 12 and anchor pipe 13. The anchor pipe 13 positions the sand and gas trap 5 the desired distance above the bottom of the well. The inlet pipes 10 are submerged in liquids such as oil and water and will normally prevent entrance of gas downward through pipes 11 and 10, thereby providing a gas anchor to entrap the gas within casing 1, as wells producing gas will normally have the casing 2 sealed at the upper end.

Each baffle member 9 has a series of circumferentially spaced upstanding tubes 14, which are secured to the baffle 9 as by screwing or welding. The upper end of each of the tubes 14 has a cap 14a secured thereto by means of set screws 14b.

It is preferable to have at least three of these set screws 14b which are circumferentially spaced and project inward through the cap 14a to engage the upper end of tube 14. In this manner the cap 14a may be adjusted, as indicated in dashed outline in Fig. 5, so that the passage between the upper end of the tube 14

and the lower surface of the cap 14a forms a restriction that will permit a given amount of oil at a given pressure to flow therethrough, which will serve as a choke to prevent the well from depleting its entire liquid reserve and "gassing," thereby losing the bottom hole pressure.

By having the cap 14a surrounding and protruding downward over the upstanding tube 14, the oil or other liquid is forced to follow a passage as indicated by the arrows, and when the oil or other liquid emerges from the annular space formed between the outer periphery of tube 14 and the inner diameter of cap 14a the sand continues to settle down into the bottom portion of each chamber, whereas the oil will turn upward and flow out through tubing 3.

By the oil flowing downward into the lower chamber or reservoir 8 into a relatively large cross sectional area a quiescent state thereof will prevail which will permit the greater portion of the sand to settle, then with the oil or other liquid passing upward through tubes 14 and downward through the annular space formed between the tube 14 and the downturned cap 14a into the large annular space formed by the inner shell 7 the remaining sand will settle out as the oil turns upward, and will be deposited in each of the chambers.

The annular space intermediate tubes 10 and shell members 6 and 7 is of much greater cross sectional area than the combined cross sectional areas of the openings within the tube 10, therefore, the oil or other liquid in which sand is entrained moves upward, after having passed down through the inlet tube 10, which will cause sand or other foreign particles to settle out into this annular space.

It is to be pointed out that a multiplicity of sections 7 may be used to make up the sand and gas trap, and that the oil containing the sand may be passed through several of these sections in order to remove the sand therefrom.

While Fig. 2 of the drawing, shows tubes 14 of the adjacent sections 7 to be in alignment, it is to be pointed out that these tubes may be spaced out of axial alignment so as to cause a zig-zag flow of oil through the chamber as defined by the intermediate tubes 7, to allow the sand to settle out of the oil.

The inlet tube 10 may be shouldered at 15 to interconnect with a section thereabove, as will best be seen in Fig. 2, and rubber gaskets 16 are provided to insure proper sealing of the tube.

It is to be pointed out that wells producing a high proportion of sand to the amount of oil may need from twelve to twenty, or even more of the sections 7 having tubes 10 and 14 therein, and each intermediate section 7 forms a separate and independent sand trap in addition to the reservoir of chamber 12.

While the invention has been described and illustrated in one embodiment thereof, it is to be understood that changes may be made in the minor details of construction, and adaptations made to suit various working conditions without departing from the spirit of the invention as claimed.

Having thus clearly shown and described the invention, what is claimed as new, and desired to secure by Letters Patent is:

1. In a sand trap for deep wells, a tubular casing comprising a plurality of shell members connected together, the uppermost of said shell members having a lateral tube therein forming an inlet therethrough, the lowermost of said shell members forming a sand receiving chamber, a baffle clamped between said shell members, said baffle having a central tube and a plurality of circumferentially spaced upstanding tubes open at their ends secured thereto for passing liquid therethrough, each of said circumferentially spaced tubes having a cover member attached thereto and spaced

from the upper end thereof and forming a passage therebetween for diverting liquid and sand passing therethrough downward so that the sand entrained within said liquid that passes through said inlet opening will settle out as the liquid passes upward through said trap, and said lateral tube forming a connection with the upper end of said central tube so as to direct said liquid and sand into said chamber formed in the lower end of said lowermost shell.

2. In a sand trap for separating solids from liquids in deep wells, a tubular casing comprising a series of shell members threaded together, the uppermost of said shell members having a lateral tube forming an inlet opening therein, the lowermost of said shell members forming a sand receiving chamber, at least one intermediate shell member having a sand receiving chamber formed therein, a baffle clamped near each pair of adjacent ends of said shell members, each of said baffles having a central tube and a plurality of circumferentially spaced, upstanding, open end tubes secured therein, each of said circumferentially spaced, upstanding tubes having a cupped member attached to and spaced from the sides and the upper, open end thereof and forming a passage therebetween for diverting said liquid passing therethrough downward so that the sand entrained within said liquid that passes through said inlet opening will settle out as the liquid passes upward through said trap, said lateral tube forming connection with the upper end of said central tube so as to direct said liquid and sand into chambers formed at the lower end of each of said shell members.

3. In a sand trap for separating solids from liquids in deep wells, a tubular casing comprising at least two shell members threaded together, the upper most of said shell members having a lateral tube forming an inlet opening therein, the lowermost of said shell members forming a sand receiving chamber, a baffle clamped near each pair of adjacent ends of said shell members, each of said baffles having a central, upstanding tube and a plurality of upstanding, open end tubes secured therein and surrounding said central upstanding tube, each of said upstanding tubes surrounding said central tube having a cupped member attached to and spaced from the sides and the upper open end thereof and forming a passage therebetween for diverting said liquid passing therethrough downward so that the sand entrained within said liquid that passes through said inlet opening will settle out as the liquid passes upward through said trap, said lateral tube forming connection with the upper end of said central tube so as to direct said liquid and sand into a chamber formed at the lower end of said shell members.

4. In a sand trap for deep wells, a tubular casing comprising a threaded tubular top shell member having an open top and a lateral tube forming an inlet opening, a threaded bottom tubular shell member closed at its lower end, a series of intermediate threaded, tubular shell members each having a shoulder internally formed a spaced distance from an end thereof, a series of baffles each having a central hole formed therein and a central, open end, inlet tube registering with the respective central holes and being secured to and upstanding from the respective baffles, the uppermost of said upstanding tubes registering with said lateral tube, a series of upstanding, circumferentially spaced tubular members positioned on said baffles around said central tube and extending upward from said baffles, each of said circumferentially spaced tubes registering with an opening formed in the respective baffles, each of said circumferentially spaced tubes having a cup attachably and adjustably secured thereto at the upper end thereof and spaced from the sides and end of the respective tubes, said tubular shell members being screw threaded together so as to present longitudinally aligned sections, one of said baffles being positioned intermediate the adjacent, longitudinally aligned, tubular shell members so

that said circumferentially spaced tubular members will extend upwardly from each of said baffles, said central tubular members below said uppermost tubular member will engage the adjacent central tubular members in end to end relation, resilient packing means fitted at the juncture of said central tubes so as to form a seal therebetween so as to form an inlet conduit through said top and intermediate tubular shell members to said bottom tubular shell member for discharging liquids and solids therethrough into said bottom tubular shell member, said circumferentially spaced tubular members interconnecting with the bottom shell member so as to convey said liquid and a portion of said sand upward therethrough with the liquid flowing out through the upper end of said top tubular shell member and a portion of said sand settling on 15 each of said baffles.

5. In a sand trap for deep wells, a series of elongated tube members forming a shell, said shell having an inlet opening and an outlet opening formed therein, an apertured baffle clamped intermediate each pair of elongated 20 tubular shell members, each of said baffles having a central tube in register with one of said apertures in said baf-

10 fle and extending upward therefrom, one end of the uppermost of said central tubes being connected with said inlet opening and the other end of said central tube being in complementary engagement with an adjacent central tube in end to end relation to form a continuous passage through said shell to a point below the lowermost of said baffles, a plurality of upstanding tubes on each of said baffles surrounding the respective central tubes, which upstanding tubes have open ends and are in register with apertures in the respective baffles, and a cover secured to and spaced from each of said upstanding tubes.
